(57) **CLAIM**

The ornamental design for a mandolin, as shown and described.

DESCRIPTION

FIG. 1 is a front perspective view of a mandolin showing my new design.

FIG. 2 is front elevational view thereof.

FIG. 3 is a bottom plan view thereof.

FIG. 4 is a rear elevational view thereof.

FIG. 5 is a top plan view thereof.

FIG. 6 is a right left side elevational view thereof; and,

FIG. 7 is a left side elevational view thereof.

The broken lines shown in FIGS. 1–7 are included for the purpose of illustrating environmental structure and form no part of the claimed design.
